No. 623,781.

Patented Apr. 25, 1899.

J. C. HACKETT.
NECK YOKE ATTACHMENT.

(Application filed Mar. 21, 1898.)

(No Model.)

Attest,
W. R. Smith,
A. J. McGehee.

Inventor:-
John C. Hackett,
By Nigdon & Longan, attys.

UNITED STATES PATENT OFFICE.

JOHN C. HACKETT, OF ST. LOUIS, MISSOURI.

NECK-YOKE ATTACHMENT.

SPECIFICATION forming part of Letters Patent No. 623,781, dated April 25, 1899.

Application filed March 21, 1898. Serial No. 674,662. (No model.)

To all whom it may concern:

Be it known that I, JOHN C. HACKETT, of the city of St. Louis, State of Missouri, have invented certain new and useful Improvements 5 in Neck-Yokes and Attachments Therefor, of which the following is a full, clear, and exact description, reference being had to the accompanying drawings, forming a part hereof.

My invention relates to neck-yokes and attachments therefor; and it consists of the novel construction, combination, and arrangement of parts hereinafter shown, described, and claimed.

Figure 1 is a plan view of a neck-yoke provided on one end with my improved attachments. Fig. 2 is a horizontal sectional view through the end of a neck-yoke provided with my improved attachments. Fig. 3 is a transverse sectional view taken approximately on 15 the line 3 3 of Fig. 2. Fig. 4 is a plan view of a modification of my improved attachment for neck-yokes. Fig. 5 is a plan view of a bearing-ring of which I make use in carrying out my invention.

Referring by numerals to the accompanying drawings, 1 indicates an ordinary carriage-pole, upon the end of which is located the neck-yoke 2. Removably located upon each end of the neck-yoke 2 is the socket 3, the 25 outer end of which may be ornamented, if desired, and formed integral with and projecting laterally from the side of the sockets 3 is a ring 4. Arranged for rotation within the ring 4 is a bearing-ring 5, the body of 30 which is semicircular in cross-section, said bearing-ring 5 being so constructed as to cover the entire inner surface of the ring 4, and projecting inwardly toward one another from the inner face of the bearing-ring 5 is a 35 pair of lugs 6.

When the strap 7, that connects the end of the neck-yoke with the horse-collar, is properly passed through the bearing-ring 5, said

strap swings freely to any position relative to the end of the neck-yoke, and thus any lateral 45 movement of the horse relative to the pole and neck-yoke is accommodated without an outside pull or side strain upon the collar worn by the horse.

In Fig. 1 I have illustrated by dotted lines 50 the latitude of the swing of the strap attached to my improved attachments for neck-yokes and also the swing of the strap attached to the neck-yoke in the ordinary manner.

In the modification shown in Fig. 4 the 55 socket 3 is split transversely, and the screw that holds said socket to the neck-yoke is located in the outer portion. When this form of the socket and ring is used, the bearing-ring 5 may be readily located in the ring 4; 60 but where a solid ring 4 is already located upon the neck-yoke and it is desired to locate a bearing-ring 5 therein said bearing-ring must be split, as indicated by the dotted line 7 65 in Fig. 5.

Thus it will be seen how I have provided a neck-yoke and attachments therefor that are simple, strong, and durable, do away with the wear between the strap from the collar to the neck-yoke, and relieve all side strain and 70 pull upon the horse's collar.

I claim—

An attachment for neck-yokes, comprising a socket, a ring integral with said socket, a bearing-ring rotatably arranged in said first- 75 mentioned ring, which bearing-ring is semicircular in cross-section and is provided on its inner face with oppositely-arranged lugs, substantially as specified.

In testimony whereof I affix my signature 80 in presence of two witnesses.

JOHN C. HACKETT.

Witnesses:

A. J. McCUALEY,
M. P. SMITH.
